CLAIM

I claim the ornamental design for a driving light mount, as shown and described.

DESCRIPTION

FIG. 1 is a front, right perspective view of a driving light mount showing our new design, according to an embodiment;

FIG. 2 is a rear, right perspective view of the driving light mount shown in FIG. 1;

FIG. 3 is a front plan view of the driving light mount shown in FIG. 1;

FIG. 4 is a rear plan view of the driving light mount shown in FIG. 1;

FIG. 5 is a left side plan view of the driving light mount shown in FIG. 1, the right side plan view of the driving light mount being a mirror image of the left side plan view;

FIG. 6 is a top plan view of the driving light mount shown in FIG. 1; and,

FIG. 7 is a bottom plan view of the driving light mount shown in FIG. 1.

The broken lines shown in the drawings represent unclaimed subject matter and illustrate portions of the driving light mount that form no part of the claimed design. The shade lines shown in FIGS. 1-7 represent surface shading and not surface ornamentation, color, or material type.
